UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

AUTOMATIC TELEPHONE-EXCHANGE SYSTEM.

1,281,348.

Specification of Letters Patent. Patented Oct. 15, 1918.

Application filed April 26, 1915. Serial No. 28,827.

To all whom it may concern:

Be it known that I, CHARLES L. GOODRUM, a citizen of the United States, residing at New York, in the county of New York and 5 State of New York, have invented certain new and useful Improvements in Automatic Telephone-Exchange Systems, of which the following is a full, clear, concise, and exact description.

10 This invention relates to telephone exchanges employing machine switching, and particularly to such systems wherein calling lines terminate in passive contacts in automatic finder switches by means of which 15 they are extended.

Ordinarily the lines are divided into groups, each group being served by a group 20 of finders to which they are multipled. The number of finders provided is usually just sufficient to take care of the maximum number of simultaneous calls. If, however, an 25 abnormally large number of calls occurs in any one group, those in excess of the number of finders are compelled to wait until busy finders are released. Thus no group could, 30 with the previous arrangements, set up more connections than there were finders allotted thereto, unless surplus finders common to the groups were provided.

35 This invention contemplates providing a circuit arrangement whereby each group may share its finders with an adjacent group, thus rendering it possible under certain conditions namely, in case a particular 40 group initiates an abnormal number of calls, to have these calls completed by finders borrowed from an adjacent group. If, then, such adjacent group has need of more finders than remain, the arrangement is such 45 that it can borrow finders of the succeeding group, and so on, experience showing that if an abnormally large number of calls is initiated in one group, it is very improbable that the succeeding group is initiating enough calls to utilize all the finders allotted thereto. By virtue of this invention therefore excess calls are taken care of without the necessity of providing surplus finders.

The invention will be clearly understood 50 when considered with regard to a specific embodiment thereof.

In the drawings, Figure 1 shows all of the apparatus individual to one subscriber's line and a portion of the apparatus individual to

another in the same sub-group, and apparatus common to the sub-group in which these two lines belong, that individual to the lines being shown to the left and that common to the sub-group to the right of the dotted line; Fig. 2 shows a line finder and 60 a first selector with their associated circuits and apparatus; Figs. 3 and 4 together, show the starter wire circuit arrangement for apportioning the finders among the sub-groups, the terminal panel being shown 65 schematically at the top of the sheet; Fig. 5 is a schematic representation of a terminal panel arranged in accordance with this invention; and Figs. 6 to 9 inclusive are views of a finder switch structure suitable for use 70 with this invention; Fig. 6 is a side elevation partly in section; Fig. 7 is a section on line 7—7 of Fig. 6 showing the switch at the top of the finder which chooses the sub-group containing the calling line; Fig. 8 is a section on line 8—8 of Fig. 6; and Fig. 9 is a section on line 9—9 of Fig. 6.

The switch structure shown in Figs. 6 to 9 inclusive will first be described.

The panel may be made up according to 80 the process disclosed in U. S. Patent 1,127,741. It is composed of strips of metal 500 and interposed insulating strips 501. Each metallic strip 500 has ears projecting 85 from opposite faces of the panel and adapted to be wiped over by the brushes of the automatic finder switches. Three of these sheets 500 are apportioned to each line.

Sets of terminals 224, 225, 226, one belonging to each of three adjacent strips 500 of 90 a given line, are adapted to be engaged by sets of brushes 221, 222, 223 of line finder switches, to extend said line to the connecting circuits to which such finders belong.

The panel or bank is divided horizontally 95 by metal bars 506 into ten divisions of ten lines each. Thus each vertical row is divided into ten sections. Each such section is served by a set of brushes 221, 222, 223 adapted to engage with the sets of terminals 224, 225, 100 226 thereof. The sets of brushes serving a given vertical row are mounted upon supports 508 which are in turn rigidly mounted upon a common carrier or rod 507. The sets of brushes are spirally arranged upon the 105 rod and the rod may be rotated by a magnet 517 to position the proper set of brushes below the desired section of the vertical row

served by the rod to which it belongs, whereupon the rod is elevated, during which movement the selected set of brushes wipes over the sets of terminals 224, 225, 226 of the section so selected. The bars 506 between the sections are made wide enough to permit the brushes to rotate without hindrance by the fixed terminals. The brush rods 507 of the finder switches are so arranged that each 10 sub-group of lines has a finder allotted thereto whose brush carrier has a set of brushes normally just below multiples of said lines, whereby no primary sub-group - choosing movement is necessary in case it is started by 15 a calling line in the sub-group to which it is allotted. Since, as will appear, a number of finders are accessible to a number of sub-groups, the circuit arrangement is such that if the finder normally assigned to any sub- 20 group is busy, another finder will be set in motion by the initiation of a call in such sub-group to connect with the terminals of such line. In this event the brush rod 507 of such finder is given a rotary movement 25 to position the brush serving the section of the vertical row, containing multiples of said lines, below said section, and thereafter a vertical movement to connect with the calling line in such sub-group. For this purpose a switch G is located at the top of each 30 finder. Each sub-group of lines is represented on this switch by a metallic segment s. These segments are adapted to be wiped over by an arm a fixed to the brush rod 507, 35 but suitably insulated therefrom. The initiation of a call in any sub-group electrically distinguishes the segment s individual thereto on the switch G, so that when the brush a reaches such segment a circuit change is 40 brought about to stop such movement, and the relation between the arm a of each rod 507 and its sets of brushes is such that when said arm has reached the segment in question, the set of brushes belonging to this line 45 sub-group is positioned just below the section containing multiples of such lines. The upward movement of the rod 507 causes the said set of brushes to wipe over the sets of terminals of this section until that of the 50 calling line is reached, when a circuit change is produced to stop such movement, whereby the calling line is connected through this finder to a selector, which is then controlled from the sender at the substation to extend 55 the connection either directly to a connector, or in case of a large exchange, first through a series of selectors.

In the event the line finder normally assigned to the sub-group containing the calling line is idle, the brush a is in contact with the segment s individual to said sub-group, and a circuit change is produced immediately upon the initiation of the call, which causes the rod 507 to move upwardly, wiping 60 the set of brushes over the sets of terminals

in the section corresponding to this calling line sub-group.

Inasmuch as the switch structure itself is not claimed herein, only a brief description thereof, necessary for a comprehension of 70 this invention, will be given.

The brush rod 507 is provided near its lower end with a gear wheel 512. The pawl 516 of the armature 517 of rotary magnet 205 does not act directly upon the gear wheel 75 512 of the rod, but steps around a rotary member 519 by engaging a ratchet wheel 521 thereon, which member carries a second gear wheel 520 which meshes with the gear wheel 512 on the rod 507. After the brush rod 507 80 has been rotated by said magnet to the proper point, the rotary magnet ceases to operate. The rod is then elevated by the pawl 524 carried by armature 523 of vertical magnet 207 mounted upon the frame 514. 85

Upon the beginning of the upward movement of the brush rod 507, a spring 525, secured to the frame, moves upwardly, a pin 526 thereon entering a notch in the gear wheel 520 to prevent the member 519 from 90 being restored by the spring 527, when the dog 528 is withdrawn later, this dog and the dog 529 of the vertical ratchet being released upon the termination of the conversation by the attractive movement of the armature of a release magnet (not shown). 95

When such release magnet is energized, the brush rod 507 drops, due to the withdrawal of dog 529. When it reaches its lowest position the shoulder 532 on the brush rod 507 presses the spring 525 against its mounting plate 533. The consequent withdrawal of the pin 526 from the gear wheel 520, permits the spring 527 to rotate the member 519, whereupon the gear wheel 520 105 restores the brush rod 507 to normal position.

Referring now to Figs. 1 and 2, a detailed description of the operation involved in connecting a calling line with a first selector through the intermediation of the finder just described will render more comprehensible a consideration of Figs. 3, 4 and 5.

Referring now to Fig. 1 the substation shown is assumed to be that of line No. 15, in the second sub-group of ten lines, and 115 the finder allotted thereto is the second, (Figs. 3, 5). The line conductors 111, 112 of this line terminate in a pair of contacts 224, 225 of the finder shown in Figs. 6 to 9. The test terminal 226 of this line is connected by a conductor 114 with the cutoff relay 120 of such line. Each subscriber's line is provided at the central office with a line relay 116 bridged across the conductors 111, 112, which becomes energized when the 120 subscriber closes the line circuit by removing his receiver. The line and cut-off relays 131, 132 of another line in the same sub-group of ten lines are also shown.

When the subscriber at substation 15 re-

moves his receiver, a circuit is closed for the line relay 116, said circuit leading over the line conductors 111 and 112 and through the telephone set of substation 15. This 5 relay thereupon closes a circuit for relay c^2 (Figs. 1, 3), to start a finder searching for this calling line, this circuit leading from the free pole of battery through the left-hand winding of line relay 116, left-hand 10 armature and back contact of the cutoff relay 120, conductor 121, contacts 117, 118, conductor g^2 , left-hand armature and back contact of relay o^2 , conductor i^2 , relay c^2 to ground. Relay c^2 thereupon locks itself up 15 in series with the line relay 116 in a circuit leading through its left-hand armature and front contact, said circuit being independent of relay o^2 . Assuming that the line finder normally associated with this sub-group be 20 idle, relay c^2 at its right-hand armature and front contact closes a circuit for the escapement magnet 217 to move the side switch of such line finder into position 2 to begin the upward movement of the brush 25 rod to cause the set of wipers of this line sub-group to test for the calling line. Under such assumption the arm a^2 of the finder brush rod is in contact with metallic segment No. 2 individual to this line sub-group 30 (as shown in Figs. 2, 3). This circuit is as follows: free pole of battery, primary magnet 205 (Fig. 2), conductor 212, side switch escapement magnet 217, conductor 218, arm 216, conductor 215, brush a^2 of the sub-group 35 switch of the finder, segment No. 2, individual to this sub-group, conductor h^2 , right-hand armature and front contact of relay c^2 to ground. Although the relay c^2 establishes a circuit for the energization of 40 slow acting relay b^2 , which through its right-hand armature grounds the conductor e^2 and apparently shunts the escapement magnet 217, it should be noted that this action does not in reality take place, 45 for by the time that slow acting relay b^2 can establish a ground on conductor e^2 it is broken at the arm 210 through the immediate action of the escapement magnet. The primary magnet 205 is so adjusted and 50 the circuit conditions are such that it does not operate when this circuit is closed. The escapement magnet 217 is however energized and is so constructed that it releases the side switch to position 2 upon its energization, in which position the circuit for the 55 said magnet 217 is maintained, this circuit being as follows: free pole of battery, magnet 205, conductor 212, escapement magnet 217, conductor 218, arm 216, now in position 60 60 conductor 287, conductors 202, m^2 , side switch arm d^2 , conductor e^2 , right-hand armature and front contact of relay b^2 , conductors h^2 , l^2 , right-hand armature and front contact of relay c^2 to ground. The 65 slow-acting relay b^2 was energized upon the energization of relay c^2 . The arm 210 of the side switch in position 2 closes a circuit for secondary magnet 207, which by interrupting its own circuit, raises the brush rod, during which movement the set of brushes 70 wipes over the sub-group of terminals containing the calling line. This circuit is as follows: free pole of the battery, secondary magnet 207, conductor 219, arm 210 and its second contact, conductors 209, 208, armature and back contact of magnet 207, conductors 268, 266, right armature and front contact of escapement magnet 217, conductor 267, conductor 204, armature and back contact of release magnet 203, conductors 202, m^2 , arm d^2 , conductor e^2 , right-hand armature and front contact of relay b^2 , conductors h^2 , l^2 , right-hand armature and front contact of relay c^2 to ground. When the finder brushes 221, 222 and 223 arrive 80 upon the terminals 224, 225 and 226 of the line of subscriber 15 initiating the call, the cut-off relay 120 of such line is energized over the following circuit: free pole of battery, relay 120, conductor 114, terminal 226, 90 brush 223, conductor 113, contacts 228, 270 of magnet 217, conductor 271, resistance 272, conductor m^2 , arm d^2 , conductor e^2 , right-hand armature and front contact of relay b^2 , conductors h^2 , l^2 , right-hand armature 95 and contact of relay c^2 to ground. Cutoff relay 120 at its left-hand armature opens the circuit of relay c^2 , which in deenergizing opens the circuit of driving magnet 207, the finder being thus brought to rest upon 100 the calling line terminals, and held there by holding pawls 528, 529 (Fig. 6). When the cutoff relay 120 operates and deenergizes the relay c^2 the escapement magnet 217 also is deenergized, and its armature in retracting 105 is arranged to release the side switch into position 3. The closure of contacts 228, 229 of magnet 217 places ground on the multiple test terminals of this line, whereby connection cannot be made to it by a connector. In 110 this position the arms 232 and 233 of the side switch connect the line conductors 111, 112 through to the line relay 234 of the selector. It will, of course, be understood that the operations involved in connecting 115 the calling line with a connecting circuit just traced take only a fraction of a second. The operation of setting the selector will not be described since it forms no part of the invention. 120

Referring now to Fig. 5, this figure represents diagrammatically a panel or flat faced bank, wherein multiples of three groups of lines of one hundred each terminate. There are twenty sub-groups of ten 125 lines each shown in Figs. 3 and 4, and thirty in Fig. 5. As shown in Fig. 5, the lines are slipped in sub-groups, that is multiples of each sub-group appear before and are accessible to ten finders, but no two sub- 130

groups are served by the same set of finders. This will be evident from a study of the said figure. Thus, lines 0-9 are accessible to the ten elevators or brush carriers numbered 1 to 10. Lines 10 to 19 skip finder No. 1, begin to appear in finder No. 2 and drop off at finder No. 11, and so on.

Referring now to Figs. 3 and 4, these figures show the starter wire arrangement. By reference to these figures and bearing in mind what has been said, it is evident that upon the initiation of a call from any sub-group of ten subscribers, since each such sub-group has an elevator or finder normally serving the same, and in position to move its brushes over the terminals thereof in the panel, no preliminary rotary movement of the elevator or brush rod of such finder to pick out this sub-group is necessary. In case, however, such finder is busy, the finders being controllable from all the lines to connect to multiples of the lines which appear before them, this sub-group is associated by an extended starter wire with the next idle finder, which in a preliminary rotary movement of its brush rod 507, positions its set of brushes 221, 222, 223 individual to such sub-group below multiples thereof and in a secondary vertical movement connects with the terminals 224, 225, 226 of the calling line therein. It will be apparent from a study of Figs. 3, 4 and 5 that the finder normally associated with a given sub-group of ten lines is the one wherein multiples of such lines begin to appear on the panel.

This will be clear from an example. Consider the second finder (Figs. 3 and 5) which is allotted to the ten subscribers 10-19 to which the substation 15 (shown in Fig. 1), belongs, is busy, and that finders Nos. 3 to 10 inclusive are also busy, and that a second call comes in from this sub-group. Line relay 131 of such line is energized by the removal of the receiver at the substation thereof and closes the following circuit to energize relay c^2 : free pole of battery, left winding of line relay 131, armature and back contact of the cutoff relay 132 of this line, contacts 117', 118', conductor 100, contacts 118, 119 of relay 116, conductor g^2 , left armature and back contact of relay o^2 , conductor i^2 , relay c^2 to ground. Relays c^2 , b^2 are energized, as before to ground conductor e^2 connected to side switch arm d^2 (Figs. 3, 2). This arm, however, is now in engagement with its third contact, and starter wire e^2 is extended by said side switch arm to conductor f^2 (Figs. 3, 2), armatures and back contacts of the relays b of the finders 3 to 9 of intervening sub-groups, through armatures and back contacts of relay b^{10} of the sub-group to which finder No. 10 is allotted to side switch arm d^{10} thereof, now in position 3, starting conductor f^{10} arm-

tures and back contacts of relay b^{11} to side switch arm d^{11} of finder No. 11, allotted to the sub-group containing lines 100 to 109, of the second group of one hundred lines, which arm will be assumed to be in engagement with its first contact connected to conductor m^{11} (corresponding to conductor m^2 of Fig. 2) which leads to the primary magnet 205 of such finder. This circuit may be continued therefore by reference to Fig. 2, and assuming the finder shown therein to be finder No. 11 of Figs. 4 and 5, the group test switch G^{11} of which finder is shown as the last of the series at the bottom of Fig. 2.

Continuing the circuit therefore by reference to Fig. 2 it leads by way of conductors m^2 , 202 of finder No. 11, armature and back contact of release magnet 203, conductor 204, armature and back contact of primary stepping magnet 205, conductor 266, conductor 268, armature and back contact of secondary stepping magnet 207, conductors 208, 209, side switch arm 210, conductors 275, 212, primary stepping magnet 205, to free pole of the battery. The magnet 205 of such finder makes and breaks this circuit, this rotating its brush rod 507, (Fig. 6). The energization of the sub-group relay c^2 , (Figs. 1 and 3) grounds conductor h^2 which is multiplied to sub-group switches G of finders 2 to 11 inclusive, (Figs. 2 to 4). When the test brush a of the sub-group switch G^{11} of line finder No. 11 therefore engages sub-group test segment No. 2 at which time the set of brushes 221, 222, 223 (Figs. 6 and 8) individual to this sub-group on the brush rod 507 of this finder, is in operative relation to multiples of this sub-group in such finder (Figs. 2 and 4), in this case nine rotary steps being necessary, a circuit is closed for the escapement magnet 217 of such finder to open the stepping circuit of rotary magnet 205. This circuit may be traced by reference to Fig. 2 as follows, still assuming the finder circuit shown in Fig. 2 to be that of finder No. 11. Ground, armature and front contact of relay c^2 (Fig. 1), conductors l^2 , h^2 , segment number 2 of sub-group switch G^{11} of finder No. 11 (Fig. 2), arm d^{11} of such switch, conductor 215 thereof, arm 216, conductor 218, side switch escapement magnet 217, conductor 212, primary magnet 205 to the free pole of battery. The escapement magnet in energizing moves its side switch to position 2, as previously described to open the primary stepping circuit and close the secondary stepping circuit. Side switch arm 210 in this position closes the circuit of secondary stepping magnet 207, whereupon the finder is moved upwardly by said magnet, in search of the calling line.

As set forth in the operation of setting up a connection, test brush 223 (Fig. 1)

during the vertical movement of the finder is connected to conductor e^2 , grounded at this time by the right-hand armature and front contact of sub-group relay c^2 by way of arm 5 d^2 , conductor m^2 , resistance 272, contact 270, 228 of magnet 217 and conductor 113. Thus when the calling line is reached and its cut-off relay 120 operated, it opens at its left-hand armature and back contact the circuit 10 of sub-group relay c^2 , as before, which in releasing, removes ground from conductor e^2 . Side switch escapement magnet 217 thereupon is deenergized and releases the side switch into position 3, and the calling 15 party is extended through to the first selector associated with finder No. 11 by side switch arms 232, 233 thereof.

While for simplicity, the segments of sub-group test switches G of the finders shown 20 in Fig. 4, (belonging to the second hundred lines), are multiplied to the sub-group test switches G of the finder of the first hundred lines, in actual practice the sub-group test switches G of Fig. 4 would be 25 multiplied to the sub-group switches G of the finders of the next succeeding hundred, and the sub-group test switches G of the finders of the last hundred would be multiplied to those of the first hundred. 30 This will be apparent from Fig 5.

While the invention has been illustrated as embodied in a finder circuit arrangement for extending calling lines to first group selectors, it will be understood that the invention 35 is not so limited, but is just as applicable to systems wherein calling lines are automatically distributed to operators' positions.

What is claimed is:

1. In a telephone exchange system, the 40 combination with lines divided into groups and sub-groups, automatic finder switches arranged in groups, sub-groups from a plurality of said groups of lines appearing in multiple terminals in finders of a plurality 45 of groups of finders and being progressively slipped therein by sub-groups, said finders being constructed and arranged to connect with said lines by a primary and a secondary movement, and means for moving said 50 finders independently upon the initiation of calls.

2. In a telephone exchange system, the 55 combination with lines divided into groups and sub-groups, automatic finder switches arranged in groups, one of said finders being normally associated with each said sub-group of lines, sub-groups of lines from a plurality of said groups of lines appearing in multiple terminals in finders of a plurality 60 of groups of finders, means for causing said finders automatically to hunt for a sub-group containing a calling line by a primary movement and for a calling line by a secondary movement, and means for causing 65 one of said finders to hunt for a calling line

by only a secondary movement when said calling line is in the sub-group to which said finder is normally associated.

3. In a telephone exchange system, the combination with lines divided into groups 70 and sub-groups, groups of automatic finder switches wherein said lines terminate in multiple contacts, said multiples being progressively slipped in said finders by sub-groups, whereby multiples of a plurality of 75 sub-groups of each group can be connected to by finders of a plurality of groups, a starting conductor for each sub-group normally associated with the finder allotted thereto, a group test switch associated 80 with each finder having a segment for each sub-group of lines, means actuated in case said finder is busy for extending said starting conductor to the next idle finder, whereby in case the finder normally assigned 85 to a sub-group is busy, the closure of the starting circuit causes the group test switch of said idle finder in a primary movement to test its group segments for the calling line group to position a brush in operative relation thereto, and means for thereupon giving the finder a secondary movement to connect with the calling line in such group.

4. In a telephone exchange system, the combination with lines divided into groups 90 and sub-groups, groups of automatic finder switches wherein said lines terminate in multiple contacts, said multiples being progressively slipped in said finders by sub-groups, whereby multiples of a plurality of 95 sub-groups of each group can be connected to by finders of a plurality of groups, a starting conductor for each sub-group normally associated with the finder allotted thereto, said finder having a brush positioned to 100 move directly over multiples of such sub-group and having other brushes individual to the other line groups, a group test switch associated with each finder having a segment for each sub-group of lines, means actuated 105 in case said finder is busy for extending said starting conductor to the next idle finder, whereby in case the finder normally assigned to a sub-group is busy, the closure of the starting circuit causes the group test switch 110 of said idle finder in a primary movement to test its group segments for the calling line group to position a brush in operative relation thereto, and means for thereupon giving the finder a secondary movement to connect 115 with the calling line in such group.

5. In a telephone exchange, automatic finder switches, lines arranged in groups and sub-groups and appearing in terminals of a plurality of said switches, each sub-group 120 of each of said groups being progressively slipped to appear in a different plurality of said switches, a finder starter circuit for each said sub-group, and means under control of said circuit for starting a single 130

one of said switches in search of a calling line.

6. In a telephone exchange system, telephone lines arranged in groups, automatic finder switches less in number than the number of lines, each said group of lines having terminals in a plurality of said switches and in a different plurality of said switches than any other of said groups of lines and each said switch having in its terminals a plurality of said groups, a finder starter circuit for each said group of lines, and means under control of said circuit for starting a single one of said switches in search of a calling line.

7. In a telephone exchange, automatic finder switches, lines arranged in groups, each said group appearing in terminals of a plurality of said switches and each said switch having in its terminals a different plurality of said groups of lines, a finder starter circuit for each of said groups of lines, and means under control of said circuit for starting said switches individually.

25 8. In a telephone system, lines arranged

in groups, automatic finder switches for extending said lines, each said group of lines having terminals in a different plurality of switches and each said switch having in its terminals a different plurality of said groups.

9. In a telephone exchange, lines arranged in groups, automatic finder switches for extending said lines, each said group of lines having terminals in a plurality of switches and each said switch having in its terminals a plurality of said groups, said groups being continuously and progressively slipped in said switches.

10. In a telephone exchange, lines arranged in groups, automatic finder switches for extending said lines, each said group of lines having terminals in a plurality of switches and each said switch having in its terminals a plurality of said groups, all of said groups being progressively slipped in said switches.

In witness whereof, I hereunto subscribe my name this 24th day of April A. D., 1915.

CHARLES L. GOODRUM.
